UNITED STATES PATENT OFFICE

FREDERICK F. BRUSH, OF CHICAGO, ILLINOIS, ASSIGNOR TO PARAGON VAPORIZER CORPORATION, OF CHICAGO, ILLINOIS, A CORPORATION OF ILLINOIS

DOUBLE FEED FUEL VAPORIZER

Application filed September 19, 1928. Serial No. 306,960.

This invention relates to a fuel vaporizer, such as are used for internal combustion engines.

In order to operate internal combustion engines, the fuel must be fed to the cylinders in finely divided form. Gasoline, the most common form of fuel, is readily converted into fine vaporized particles. The heavier hydrocarbons are not so easily convertible, yet their use would result in considerable economy. Such heavier hydrocarbons do not vaporize at ordinary room temperatures; and even if external heat be applied, such as by the aid of the exhaust gases, the vaporization is apt to be imperfect.

It is one of the objects of my invention to provide a novel and simple vaporizer for the heavier hydrocarbons, that will convert the fuel into readily usable form.

I accomplish this result by providing a gravity feed for the fuel along the inner surface of a conduit heated by the exhaust gases. Such an arrangement works quite satisfactorily for engines having one or two cylinders, or for engines of small size, in which the intake manifold is rather short. In larger sizes, or where a manifold is used having a number of parallel paths, I find it advantageous to ensure that the vaporized fuel is fed uniformly to all parts of the manifold, for otherwise some of the cylinders may receive more fuel than the others. Accordingly it is another object of my invention to provide a scheme whereby an even distribution of fuel is obtained, so that in spite of the existence of unvaporized particles in the fuel, all cylinders will obtain a fair proportion of the entire fuel charge.

For this purpose, I provide a split conduit in which the vaporization is effected, each portion of the conduit leading to a definite set of cylinders. In this way, as the operation of the cylinders serves to suck in a charge of fuel and air through the conduit, the suction is alternated between the sections of the conduit, and fuel is independently drawn (as by the aid of a Venturi opening) by the suction into each section as needed.

My invention possesses many other advantages, and has other objects which may be

made more easily apparent from a consideration of one embodiment of my invention. For this purpose I have shown a form in the drawings accompanying and forming part of the present specification. I shall now proceed to describe this form in detail, which illustrates the general principles of my invention; but it is to be understood that this detailed description is not to be taken in a limiting sense, since the scope of my invention is best defined by the appended claim.

Referring to the drawings:

Figure 1 is a diagrammatic, sectional view showing one embodiment of my invention; and

Fig. 2 is an enlarged section taken along plane 2-2 of Fig. 1.

In Fig. 1, I show an engine 11, having two or more intake openings 12, and corresponding outlet openings 13; each of these openings, as is well understood, being associated with a cylinder. The intake manifold 14, leading to both intake openings 12, has an air inlet 15, through which air is sucked on the intake stroke of any of the pistons. A throttle valve 16 can be provided in this passageway.

The suction thus created causes a spring pressed valve 17 to open. This valve can be of conventional design, and arranged to pass the air downwardly through a carburetting device. This device will be now more thoroughly described.

Fuel is arranged to be commingled with the stream of air flowing downward past the valve 17. In order to increase the velocity of the air where the fuel enters so as to pull the fuel into manifold conduit 14 readily, it is preferred to provide a constriction, or a venturi, in this conduit. Thus I show apertures 18, 19, leading from a float chamber 20 (Fig. 2) that is supplied with liquid fuel, into the conduit 14. Both apertures 18, 19 can be controlled as by needle valves 21, 22 extending outside of the float chamber for ready manipulation.

The conduit 14 is surrounded by the outlet manifold 23 to impart heat to this conduit, the exhaust gases finally emerging from the outlet opening 24. The fuel flows down the sides

of conduit 14, and is vaporized by the heat developed in the exhaust manifold 23. Whatever is left unvaporized drips into pockets 25 in the bottom portion 26 of manifold 14, and is there later vaporized by the heat.

5 One of the important features of my invention resides in the provision of separate passageways in conduit 14, whereby the fuel feed to a part of the cylinders is entirely separate from the feed to the other cylinders. In this way, it is assured that each set of cylinders will receive its full quota of fuel, even if the manifold 14 is of such a character that it does not provide smooth and easy passageways for the fuel. Thus there is a partition wall 27 in conduit 14, dividing the conduit into two portions, each controlled by either of the throttle valves 28 and 29, and each having independent Venturi openings 30, 31. In this 10 way the feeding of the mixture of fuel and air to both parts of the manifold is made substantially uniform.

15 I claim:

In a fuel vaporizer for an internal combustion engine having a plurality of substantially vertical passageways, each passageway leading to a different group of the cylinders, means for dripping liquid fuel into each passageway so that the fuel forms a layer on the inner surface thereof, means for heating the passageways, means providing a space in the manifold where the unvaporized fuel can collect by gravity, and means for heating said space.

20 35 In testimony whereof I have hereunto set my hand.

FREDERICK F. BRUSH.
